UNITED STATES PATENT OFFICE.

HULBERT BYXBE, OF WILLIAMSPORT, PENNSYLVANIA.

IMPROVEMENT IN PLATEN-GAUGES.

Specification forming part of Letters Patent No. 123,233, dated January 30, 1872.

To all whom it may concern:

Be it known that I, HULBERT BYXBE, of Williamsport, in the county of Lycoming and State of Pennsylvania, have invented a new and valuable Improvement in Combined Gauges and Guides for Printing-Presses; and I do hereby declare that the following is a full, clear, and exact description of the construction and operation of the same, reference being had to the annexed drawing making a part of this specification and to the letters and figures of reference marked thereon.

Figure 1 of the drawing is a representation of a plan view of my invention. Fig. 2 is a side view of the same.

This invention has relation to attachments for job printing-presses; and consists in the novel construction and arrangement of devices used in connection with the platen, and designed for the purpose of gauging the position of and guiding the sheet or card to be printed on.

In the accompanying drawing illustrating this invention, A represents the platen of a printing-press; B, the tympan-sheet held by the metallic rim C; D D, a pair of gauge-bars designed to rest on the platen above the tympan-sheet. These bars are bent down at their ends so as to clamp the rim C, and are secured by means of a thumb-screw, d, at the upper end of each. The bars D are graduated to inches and fractions of an inch from end to end or to any extent. E E represent guide-bars, constructed with eyes e at their outer ends to slide over the gauge-bars, which lie on the platen parallel to each other. The bars E extend at right angles to the bars D, and at the inner

ends are constructed with ears d². Said bars E are adjustable along the gauge-bars to suit the size of the sheet or card or the position of the printed matter, and are held at any suitable place by means of the thumb-screw d¹, which passes through the eyes e and touches the bars D. The bars D may be brought as close together or moved as far apart as may be required. The sheet or card is laid on the tympan with its lower edge resting on the ears d². The guides E should be made thin enough to let the nippers pass over them so as to take hold of the sheet. The bars D are to be made long enough to allow of a sheet or card being adjusted to the lower extreme edge of the platen. Side guides may be used with the gauge-rods D and regulated or adjusted in the same manner as the guides marked E. Gauge-rods secured to the platen and extending below it may also be used, guides working similarly to those shown being employed with the extensions. The bars E are made elastic and slightly bent, so as to press against the tympan-sheet.

I claim as my invention—

The graduated bars D, bent at their ends and secured to the platen of a printing-press by means of screws d, in combination with the guards E having the eyes e, lugs d², and held in place by means of the screws d¹, substantially as described and shown.

In testimony that I claim the above I have hereunto subscribed my name in the presence of two witnesses.

HULBERT BYXBE.
